UNITED STATES PATENT OFFICE

THOMAS HENRY JONES, OF WOODTHORPE, ENGLAND

CIRCULAR KNITTING MACHINE

Application filed June 17, 1929, Serial No. 371,582, and in Great Britain July 21, 1928.

This invention comprises improvements in or relating to circular knitting machines and in the production of fabric thereon and has for its object to provide means by which a tubular fabric having the characteristics of a shogged or racked fabric can be produced by a small number of threads relatively to the number of needles or number of stitches in a course, even for example, by a single thread.

According to the present invention a circular knitting machine is provided embodying a plurality of sets or rows of needles, stitch-forming cams associated with said needles, means for feeding yarn to said needles, means for effecting relative motion between the needles and the stitch cams, means whereby certain of the needles operate to draw loops in one direction and others of said needles operate to draw loops in an opposite direction, the number of needles in one set being different from that in another set, and means for varying the disposition of one set relatively to another during operation.

Another feature consists in providing a circular knitting machine embodying concentric needle carriers, associated cams and yarn feeding means, means whereby certain of the needles operate to draw loops in an opposite direction to the remaining needles, said carriers containing a dissimilar number of needles and means for rotating said carriers progressively relatively to each other.

A further feature resides in a machine having one or more of the above-named features and characterized in that at each revolution of the machine there is always a predetermined number of definite positions or nodes at which a needle or needles in each carrier are suitably disposed relatively to each other for cam operation, yarn feed and mutually meshed stitch formation.

Yet another feature resides in providing intermediate of the positions or nodes at which mutually meshed stitches are formed cams coacting with needles of only one of the needle carriers.

In one method of carrying out this invention a circular knitting machine is employed

having two needle carrying members, hereinafter called dial and cylinder, concentric with each other, cams being associated with said carriers for coacting with the needles to draw and form loops of thread supplied from one or more suitable yarn feeds, the loops being drawn in opposite directions to produce a ribbed fabric.

In the production of ordinary ribbed knitted fabric it is well known that the dial and cylinder contain an equal number of needles, the needles of one member being adapted to project between the needles of the other member and the two members being rotated at an equal speed in the same direction. In this way fabric is made wherein the needle wales produced by one set of needles are parallel with those produced by the other set.

By providing an equal number of needles in both carriers, it is of course essential that the carriers be rotated at equal speeds or that the relative positions of the two sets of needles are never varied, as should such carriers be revolved at different speeds the needles will be moved into unsuitable relationship for mutual action and will foul each other.

However, if the number of needles in the one carrier be one in excess of the needles in the other carrier, and the needles in the two carriers are so positioned that one needle in each carrier occupies the same radial position, the needles on either side of this point of coincidence will occupy positions of cumulative divergence until at a diametrical opposite position to the said point of coincidence a needle of the dial will occupy a radial position exactly midway between two needles of the cylinder and be in the best position for operation by the cams to form mutually meshing loops.

If now the carrier containing the larger number of needles be revolved at a suitably reduced speed relatively to the speed of rotation of the carrier containing the smaller number of needles, there will always be at a given position a point of coincidence between a needle of each set and consequently there will always be a point at which a needle of one set is located midway between the two needles of the other set, that is to say in a

position for cam operation, yarn feed and mutual stitch formation. In other words, the relative positions of any pair of needles consisting of one needle of each carrier will always be the same at a fixed point at any given time, successive needles gradually assuming the position of such pair as they approach the said fixed point and gradually diverging as they recede from the fixed point.

For example, it may be assumed that the cylinder contains fifty needles and the dial fifty-one, in which case the cylinder would be revolved fifty-one times while the dial revolved fifty times.

By doubling the number of needles contained in each carrier, that is to say, by providing two more needles in the one carrier than in the other, it will be appreciated that there will be two points of coincidence and two points or nodes at which knitting can take place, while if the number of needles in each carrier is quadrupled there will be four points or nodes, and it is to be understood that at each of the knitting points or nodes a yarn feeder and needle operating cams must be provided unless it is desired to rack or shog more than one needle space.

By providing a dissimilar number of needles in the two carriers and effecting relative displacement of the carriers as above described, the needle wales produced in the fabric by the one set of needles are caused to extend at an angle to the needle wales formed by the other set of needles, that is to say, the one set of needle wales will be continuously shogged or advanced laterally in one direction relatively to the needle wales formed by the other set, while additionally the successive stitches or loops of each needle wale appertaining to the one set of needles will mesh with stitches appertaining to successive needle wales formed by the other set of needles. For example, a fabric may be produced wherein the needle wales of one set are vertical while those of the other set extend in the form of a spiral having a pitch of one stitch advance per course, the spiral wales thus being disposed practically at right angles to the vertical wales.

The needles of both sets can only be operated together for producing mutually meshing stitches at the aforesaid knitting points or nodes, but it is to be understood that the needles of either set may be operated independently of those of the other set at any point so as to produce one or more courses of plain knitting on the one face of the fabric.

For the purpose of more fully describing the nature of this invention, reference will now be made to the accompanying drawings, wherein:

Figure 1 is a vertical section of a circular knitting machine in accordance with this

invention for producing shogged rib fabric taken on the line II—II of Fig. 2.

Figure 2 is a plan view of the same.

Figure 3 is a plan view of a modified construction of machine.

Figure 4 is a vertical section IV—IV of Figure 3.

Referring to Figures 1 and 2 the cam box 3 is rotated relatively to the cylinder 1 from the main drive 2 through the intermediary of bevel 4 and gear 5, the dial cam plate 6 being connected to rotate in unison with the cam box 3 through the intermediary of upstanding posts 7 and links 8. The dial needle carrier 9 is retained stationary while the cylinder 1 is rotated very slowly relatively to said dial so as to produce the necessary shogged effect in the fabric. This comparatively slow rotation of the cylinder may be effected from the rotating cam box 3 through the intermediary of a gear 10 on said box meshing with a bevel 11 rotating on a fixed axis having rotating in unison therewith a worm 12 engaging a worm wheel 13 rotating on a fixed vertical axis, a small gear 14 rotating in unison with the worm wheel 13 coacting with peripheral teeth on a flange 15 of the cylinder 1.

In the arrangement illustrated eight thread feeds 16 are provided equidistant around the machine, therefore as the cylinder 1 is rotated slowly relatively to the fixed dial 9, said dial contains eight more needles than the cylinder.

Several methods of producing fabric on a shogged rib machine as previously described may be employed. For example a thread may be fed to both sets of needles 1a and 9a simultaneously when in a protruded position projecting between each other which is the normal manner of producing ribbed fabric.

In Figures 3 and 4 a rib knitting machine is illustrated having two thread feeds 16 at diametrically opposite positions, the cylinder cam box 17 is stationary, as also is the cam 18 which operates upon the dial needles 19. The drive is transmitted from the main shaft 2 through intermeshing bevels 20, 21, to the needle cylinder 1, and from said cylinder drive is transmitted to a rotary dial needle sley 22, the rotation of the needle dial 23 being in this arrangement effected through the needles 19 themselves which depend from the sley 22 into the trickeh dial 23. The drive from the cylinder 1 to the rotating sley 22 and thence to the dial 23 is such as to cause said cylinder and dial to rotate at relatively different speeds, and this transmission of drive may be effected as illustrated from a circumferential gear 24 on the cylinder to a gear 25 on the lower end of a vertical spindle 26 rotating on a stationary axis, a gear 27 at the upper end of such spindle meshing with a toothed flange 28 on the sley 22.

As will be evident to those skilled in the

art, the means for and method of rotating one needle carrier relatively to another may be varied in many ways without departing from the scope of the present invention.

5 A fabric produced upon a machine such as herein described and claimed is illustrated, described and claimed in my application filed concurrently herewith, and bearing Ser. No. 371,560.

10 I claim:—

1. A circular knitting machine comprising a plurality of sets of needles, stitch-forming cams associated with said needles, means for feeding yarn to said needles, means for effective relative motion between the needles and the stitch cams, means whereby certain of the needles operate to draw loops in one direction and others of said needles operate to draw loops in an opposite direction, the number of needles in one set being different from 15 that in another set, and means for progressively varying the disposition of one set relatively to another during operation.

2. A circular knitting machine embodying concentric needle carriers, associated stitch forming cams, yarn feeding means, means for effecting relative movement between the needles and stitch cams, means whereby certain of the needles operate to draw loops in an 20 opposite direction to the remaining needles, the needle carriers containing a dissimilar number of needles and means for producing progressive relative rotation between the said carriers.

3. A circular knitting machine comprising a plurality of sets of needles, stitch-forming cams associated with said needles, means for feeding yarn to said needles, means for effecting relative motion between the needles and the stitch cams, means whereby certain of the needles operate to draw loops in one direction and others of said needles operate to draw loops in an opposite direction, the number of needles in one set being different from 25 that in another set, means for progressively varying the disposition of the needles of one set relatively to those of another and said means operating so that at each revolution of the machine there is always a predetermined number of definite positions or nodes at which a needle or needles in each carrier are suitably disposed relatively to each other for cam operation, yarn feed and mutually meshed stitch formation.

4. A circular knitting machine embodying concentric needle carriers, stitch cams, yarn feeding means, means whereby needles of one carrier draw loops in an opposite direction to needles of another carrier, the number of 30 needles in one carrier being different from that in another carrier, means for effecting progressive relative rotation between the carriers containing a dissimilar number of needles, means whereby at each revolution of the 35 machine a predetermined number of posi-

tions occur at which mutually meshed stitches can be formed on needles of the relatively movable carriers, cam means functioning to operate upon the needles of only one carrier and said cam means operating intermediate of the positions at which mutually meshed stitches are formed.

5. A circular knitting machine embodying a cylinder, needles operable therein, cam means coacting with said cylinder needles, 70 a dial concentric with and interiorly of said needle cylinder, needles operable in said dial, cam means associated with and operating upon the dial needles, the number of needles in the cylinder being different from that in the dial, means for feeding yarn to the needles, and means whereby progressive relative rotation is effected between the cylinder and dial so as to vary continuously the disposition of one set of needles relatively to the other.

6. In a circular knitting machine, concentric needle carriers, stitch forming cams associated with each carrier, yarn feeding means, needles of one carrier operating to draw loops in an opposite direction, to needles of another carrier, the number of needles in one carrier being different from that in another carrier and means for imparting progressive relative movement to the said carriers whereby the said needle carriers, needle cams and 95 yarn feeding means are all traversed at suitable relative, but different, speeds.

7. In a circular knitting machine, two concentric needle carriers, the needles in one carrier operating to draw loops in an opposite direction to the needles in the other carrier, knitting cams associated with each carrier, means whereby yarn from each of a plurality of feeders is fed to and knitted on alternate needles in each carrier, one of said carriers containing a greater number of needles than the other carrier, and means whereby relative progressive motion is imparted to one of the two needle carriers relative to the other.
